ELEVATOR LUBRICATOR

Edward R. McKenzie, Memphis, Tenn.

Application September 18, 1933, Serial No. 689,906

4 Claims. (Cl. 184—21)

This invention relates to lubricating devices and is particularly intended for the lubrication of guide rails for elevators and other apparatus in which guide rails are employed.

In elevator practice, the elevator cages are guided in their upward and downward movement by guides or rails which usually are T-shaped structural members. It is necessary to constantly lubricate these rails, if unsufficient lubrication is supplied trouble arises, but on the other hand, if too much lubricant is applied, there is not only the expense of the wasted lubricant, but perhaps more important is the resulting uncleanliness, which in many cases is not only unsightly, but may cause actual damage to the clothes of passengers in the elevator. In an endeavor to get away from these troubles a hard grease in stick form, has been adopted and various methods have been tried out whereby to advance the stick endwise against the edge and sides of the rail. In general, the advancement of the stick has been by a mechanical step by step movement, or by the pressure exerted by a spring. Mechanical advancement, while having many advantages, is complicated, on the other hand where a spring is used difficulty has been experienced owing to the initial length of the grease stick, to secure a light enough pressure at the beginning of the feed without getting an inadequate pressure at the end of the feed. Difficulty has also been experienced in confining the grease so that excessive wastage and uncleanliness may not occur.

The primary object of the invention is to provide a simple and convenient device through the medium of which lubricant in comparatively hard, or stick, form may be applied to the edge and sides of an elevator guide rail;

Further objects are:

To provide a device of the character described in which waste of the lubricant is minimized, and in which an even distribution of the lubricant particularly to the sides of the rail is accomplished;

To provide means by which resilient pressure may be applied with a minimum of variation throughout the length of the charge; and generally

To improve the design of and simplify the construction of such a device.

The means by which the foregoing and other objects are accomplished and the manner of their accomplishment will readily be understood from the following specification by reference to the accompanying drawing, in which:

Fig. 1 is a side elevation of the device showing its relation to the elevator rail;

Fig. 2 is a vertical sectional elevation taken on the longitudinal center line of the device;

Fig. 3 is a sectional plan taken as on the line III—III of Figs. 1 and 4;

Fig. 4 is an end elevation on approximately double the scale of the previous views, a portion of the end of the device being broken away; and

Fig. 5 is an end elevation of the opposite end of the device this figure being on the same scale as Figs. 1 to 3 inclusive.

Referring now to the drawing in which the various parts are indicated by numerals, 10 is an elevator rail shown only in Figs. 1 and 3; 11 is a fragmentary portion of a stick of the lubricant shown only in Fig. 2. 12 is a fragmentary portion of a member forming part of the elevator cage to which the present device is attached as by cap screws 13.

The device comprises a body 14 of hollow structure for the reception of the stick of lubricant 11. 15 is a complementary hollow cover, adapted to complete with the body a hollow substantially cylindrical casing or barrel conforming in interior diameter to the size of the lubricant stick to be used therewith. Lugs 16 projecting from the body, and corresponding lugs 17 from the cover, are pin connected to form hinges connecting the body and cover. 18 is a spring latch secured to the cover 15, and adapted to engage a flange portion 19, of the body, to hold the cover in place when closed.

The body 14, preferably is secured to a bracket 20 as by bolts 21, and the bracket in turn secured to the elevator member by the cap screw 13.

The rear or outer end of the barrel may be closed by a head 22. A hollow front end 23 forms an extension of the barrel, the extension being of hollow cylindrical conformation at its junction therewith, and being slotted to form jaws 24, which lie on opposite sides of the rail 10. These jaws are lined with a resilient packing 25, preferably leather which closely embraces the sides of the rail. This lining extends at 26 into a cylindrically chambered portion of the extension 23, and is hollowed out at 27 in conical form to effect a continuation of the cylindrical bore of the barrel, the passageways thus formed terminating short of the marginal edges of said lining whereby said lining in connection with said rail form a closure for said passageways and said lining acts to evenly distribute the lubricant to the sides and edge of said rail.

6 The lower portion of the body is provided with a longitudinal slot 30, through which an arm 31 extends into the bore of the device. 32 is a disk or follow block carried by the arm 31. The outer end of the arm is provided with a head 33 which is slidably mounted on a guide rod 34 disposed parallel to the body 14.

10 The guide rod is carried by brackets 35 depending from the body 14. 36 is a flexible connector, preferably a thin metal tape, one end of which is secured to the arm 31. This tape passes around a pulley 37 and to a reel 38 which is actuated by a spring 39, one end of the spring as usual, being secured to the reel and the other to a hollow shaft 40 which also carries a ratchet wheel 41, which is integral with the shaft. 42 is a double acting dog having lugs 42A, 42B, which are adapted to be alternately engaged with the teeth of the ratchet wheel 41, disengagement of one lug permitting another tooth of ratchet wheel to move backward against the other lug which is disposed in its path. Either of said lugs holds the ratchet wheel against rotation by the spring. Such dog also by rocking action allows the ratchet wheel to turn, step by step, to loosen the spring, or to be manually advanced step by step to tighten the spring. Shaft 40 is rotatably mounted on a stud 43, which is carried by a bracket 44, secured to the end bracket 35.

15 In use the device is mounted on a convenient portion of an elevator cage to move upward and downward therewith with the lined jaws 24 engaging the sides of the guide rail 10, and the portion 26 of the lining engaging the edge of the rail. The latch 18 is disengaged, allowing the cover 15 to be opened. Follow block 32 is forced rearwardly against the spring action, and a stick 11, of hard grease dropped into the hollow body 14. Follow block is then released to engage the grease stick and move it against the edge of the rail 10.

20 If not properly tensioned the spring 39 may be loosened by rocking the dog to permit step by step retrogression of the ratchet wheel and attached shaft 40, or may be tightened by manually turning the ratchet wheel while similarly rocking the dog.

25 Pressure of the follow block against the grease stick, eventually causes the grease to flow through the tapering passageways 27 against both sides of the rail, the leather jaw lining preventing escape of the grease outward or upward and downward along either the sides or edge of the rail. Under the action of the grease the leather lining is softened and swells into closer contact with the rail, it also acts as a swab to evenly distribute a thin film of grease on the rail and accomplish that even distribution of grease which is desired.

30 It will be obvious that modification of various details hereof may be made without departing from the spirit of my invention and it is to be understood that I do not wish to limit myself to detail except as it may be set out in the claims hereto appended.

Having described my invention, what I claim is:

35 1. A device for lubricating elevator rails, comprising a hollow barrel adapted to receive a lubricant, a spring actuated follow block therein, said barrel having an extension slotted to form jaws adapted to lie on opposite sides of an elevator rail, and a resilient lining carried by said extension and supported by said jaws, said lining embracing the sides and an edge of said rail, and having a bore forming a continuation of the

bore of said barrel and tapering on each side toward said rail, said taper terminating inward from the marginal edges of said lining, whereby to form passageways leading from said bore to the sides of said rail, the marginal edges of said lining forming means for confining and distributing grease to said rails.

40 2. A device for lubricating elevator rails, comprising a hollow barrel adapted to receive a lubricant, a follow block therein, and means for exerting pressure on said follow block to advance lubricant in said barrel, said barrel having an extension slotted to form jaws adapted to lie on opposite sides of an elevator rail, and a resilient lining carried by said extension and supported by said jaws, said lining embracing the sides and an edge of said rail, and having a bore forming a continuation of the bore of said barrel, said bore extending beyond the edge of said rail, and tapering on each side toward said rail, said tapered portion terminating inward from the marginal edges of said lining, whereby to form passageways leading to the sides of said rail, the marginal edges of said lining forming means for confining and distributing grease to said rails.

45 3. A device for lubricating elevator rails, comprising a hollow barrel adapted to receive a lubricant, said barrel having an extension slotted to form jaws adapted to lie on opposite sides of an elevator rail, and a resilient lining carried by

50 said extension and supported by said jaws, said lining embracing the sides and an edge of said rail, and having a bore forming a continuation of the bore of said barrel and tapering on each side toward said rail, said tapering portion terminating inward from the marginal edges of said lining, whereby to form passageways leading to the sides of said rail, the marginal edges of said lining forming means for confining and distributing grease to said rails.

55 4. A device for lubricating elevator rails, comprising a hollow barrel adapted to receive a lubricant, said barrel having an extension slotted to form jaws adapted to lie on opposite sides of an elevator rail, and a resilient lining carried by

60 said extension and supported by said jaws, said lining embracing the sides and an edge of said rail, and having a bore forming a continuation of the bore of said barrel and tapering on each side toward said rail, said tapering portion terminating inward from the marginal edges of said lining, whereby to form passageways leading to the sides of said rail, the marginal edges of said lining forming means for confining and distributing grease to said rails; and means for advancing lubricant within said barrel toward

65 said rail, comprising a follow block disposed within said barrel, an arm carrying said block and extending outward through said barrel, said barrel being longitudinally slotted to permit sliding movement of said arm, a longitudinally disposed

70 guide for the outer end of said arm, a reel carried by said barrel, a coil spring actuating said reel, and a flexible connector secured at one end to said reel and at the opposite end to said arm, whereby a spring of relatively long range of action

75 comparative to the movement of the follow block may be used and a substantially even spring pressure be exerted on said lubricant throughout the entire movement of said follow block.

80 5. A device for lubricating elevator rails, comprising a hollow barrel adapted to receive a lubricant, said barrel having means for leading lubricant therein to an elevator rail, means for advancing lubricant within said barrel toward said rail, comprising a follow block disposed within

85 said barrel, an arm carrying said block and extending outward through said barrel, said barrel being longitudinally slotted to permit sliding movement of said arm, a longitudinally disposed

90 guide for the outer end of said arm, a reel carried by said barrel, a coil spring actuating said reel, and a flexible connector secured at one end to said reel and at the opposite end to said arm, whereby a spring of relatively long range of action

95 comparative to the movement of the follow block, may be used and a substantially even spring pressure be exerted on said lubricant throughout the entire movement of said follow block.

100 6. A device for lubricating elevator rails, comprising a hollow barrel adapted to receive a lubricant, said barrel having an extension slotted to form jaws adapted to lie on opposite sides of an elevator rail, and a resilient lining carried by said extension and supported by said jaws, said lining embracing the sides and an edge of said rail, and having a bore forming a continuation of the

105 bore of said barrel and tapering on each side toward said rail, said taper terminating inward from the marginal edges of said lining, whereby to form passageways leading to the sides of said rail, the marginal edges of said lining forming means for confining and distributing grease to said rails.

110 7. A device for lubricating elevator rails, comprising a hollow barrel adapted to receive a lubricant, said barrel having an extension slotted to form jaws adapted to lie on opposite sides of an elevator rail, and a resilient lining carried by

115 said extension and supported by said jaws, said lining embracing the sides and an edge of said rail, and having a bore forming a continuation of the bore of said barrel, said bore extending beyond the edge of said rail, and tapering on each side toward said rail, said tapered portion terminating inward from the marginal edges of said lining, whereby to form passageways leading to the sides of said rail, the marginal edges of said lining forming means for confining and distributing grease to said rails.
